UNITED STATES PATENT OFFICE.

GEORGE W. MCGILL, OF RIVERDALE-ON-HUDSON, NEW YORK.

SPRING-CLIP.

SPECIFICATION forming part of Letters Patent No. 743,017, dated November 3, 1903.

Application filed March 26, 1903. Serial No. 149,715. (No model.)

To all whom it may concern:

Be it known that I, GEORGE W. MCGILL, a citizen of the United States, and a resident of Riverdale-on-Hudson, in the county of New York and State of New York, have invented 5 certain new and useful Improvements in Spring-Clips, of which the following is a specification.

My invention has for its object to provide 10 a novel, simple, and effective spring-clip made of a single piece of suitable spring-wire and which is susceptible of being rapidly and economically manufactured, which may be readily applied in securing together papers 15 and similar articles, and which will be free from all tendency to abrade, deface, or tear the papers or other articles to which it may be applied or to work loose or displace itself from its correct position thereon while in use.

20 In the accompanying drawings, making part of this specification, and in which similar reference letters and numerals indicate corresponding parts, Figure 1 represents a side view of one configuration of the clip. Fig.

25 Fig. 2 is a similar view in perspective of a modified construction of the clip. Fig. 3 is a top view of Fig. 2. Figs. 4 and 5 are side views 30 in perspective of the clip, showing in each figure, respectively, the top of the clip modified. Fig. 6 is a view similar to Fig. 5 and showing the clip applied in securing together several sheets of paper.

The clip is provided with a frame or body part 35 resembling somewhat in its configuration the letter X, in which the single round wire from which it is fashioned is folded in manner to provide a top part or spanning-saddle, with the wire continued from the ends thereof in two converging and depending arms, which 40 near their center are folded up adjacent to and parallel with themselves and in the same plane in manner to provide them two auxiliary members, the arms proper crossing each other diagonally below the center of the 45 saddle in manner to provide between them a space in which to receive the edges of the articles being clipped and facilitate the after entrance of the latter between the superimposed surfaces of the clip.

50 In the drawings, A represents the top of the clip, or what I designate its "spanning-sad-

dle." b b' represent the ends or shoulders of the same; 1 1', the depending arms of the clip; c c', the central folds or elbows of the latter, and 2 2' the auxiliary members of such 55 arms.

In constructing the clip the wire is first folded down in manner to provide the top part or spanning-saddle A, the shoulders b b', and the depending arms 1 1', the latter being 60 folded upwardly at their elbows c c' on lines adjacent to and parallel with their lower looped parts and in the same plane therewith, providing the arms their auxiliary members 2 2'. The arms are now crossed diagonally 65 below the saddle at e in manner to provide an angular space between their looped parts in which to receive the edges of the articles being clipped. The members 2 2' of the arms may then be continued up toward the saddle 70 A without bending, as shown in Fig. 1, or be bent at the points marked d d' in manner to diverge outwardly from those points into alinement and continuous spring-bearing with the upper part of the opposite arms, as 75 shown in all the other figures of the drawings.

The top or spanning-saddle of the clip may be straight, as shown in Figs. 1, 2, and 3, or provided with an arched center, as shown at g in Fig. 4, or made wholly arched, as shown 80 in Figs. 5 and 6, the arching of the whole or part of the top or saddle providing better results in the clamping feature of the device where a limited number of papers are being clipped by admitting of the shoulders of its 85 top or saddle resting below the clipped edges of the papers, and the ends of the wire forming the clip may extend upward beyond its shoulders, as shown in Fig. 2, and be provided with bulbous terminals transversely projected 90 from opposite sides of the clip across the plane of its top or saddle, as shown at f f' in Figs. 2 and 3, the object of such opposite transverse projections of the wire terminals being to hold the flat top of the clip in proper position upon the clipped edges of the paper and of their bulging to save the papers from being abraded by them. The wire in the top or spanning part of the clip is flattened and widened vertically throughout its length by 95 compression in manner to increase its resistance to the torsional strain to which it is sub-

jected on papers and other like articles being inserted between the bearing-surfaces of the resilient clamping-arms of the device.

The clip thus constructed is applied in 5 clamping and securing together papers and like articles by introducing the edges of the latter into the angular-shaped space *e*, intermediate the folds *c c'* of the clip-arms, and pressing the clip down upon the papers until 10 its top or saddle *A* rests upon the same, spanning and riding it diagonally, with its superimposed arms bearing against the opposite surfaces of such papers and clamping the latter between them, as shown in Fig. 6, in which 15 *H* indicates the papers.

I claim—

1. An **X**-shaped spring-clip composed of a single wire folded at its center in manner to provide the clip a top part or saddle having 20 an arm depending from each end thereof and converging below it in manner to cross each other some distance beneath its center, both of the arms below such crossing being folded upwardly in manner to provide them two auxiliary members occupying lines adjacent to and parallel with that part of the arms depending below such crossing, and such auxiliary members continued upward toward the top 25 of the clip, along the upper part of the opposite arms, and in continuous spring-bearing therewith.

2. An **X**-shaped spring-clip composed of a single wire folded at its center in manner to provide the clip a top part or saddle having 30 an arm depending from each end thereof and

converging below it in manner to cross each other some distance beneath its center, both of the arms below such crossing being folded upwardly in manner to provide them two auxiliary members occupying lines adjacent to 40 and parallel with that part of the arms depending below such crossing, and such auxiliary members continued upward toward the top of the clip.

3. An **X**-shaped clip composed of a single 45 wire folded at its center in manner to provide the clip a top part or saddle having an arm depending from each end thereof and converging below it in manner to cross each other some distance beneath its center, both of the 50 arms below such crossing being folded upwardly in manner to provide them two auxiliary members occupying lines adjacent to and parallel with that part of the arms depending below such crossing, and such auxiliary members continued upward toward the 55 top of the clip, the wire in such top being flattened and widened vertically throughout its length by compression in manner to increase its resistance to the torsional strain to which 60 it is subjected on papers and other like articles being inserted between the bearing-surfaces of the arms of the device.

Signed at Riverdale-on-Hudson, in the county of New York and State of New York, 65 this 2d day of August, A. D. 1902.

GEORGE W. MCGILL.
